UNITED STATES PATENT OFFICE.

ROBERT STEINER, OF GRATZ, AUSTRIA.

BOBBIN-WINDER.

SPECIFICATION forming part of Letters Patent No. 258,494, dated May 23, 1882.

Application filed October 18, 1881. (No model.)

To all whom it may concern:

Be it known that I, ROBERT STEINER, a citizen of Austria, residing at Gratz, in the Province of Steiermark and Empire of Austria, 5 have invented new and useful Improvements in Bobbin-Winders, of which the following is a specification.

This invention relates to bobbin-winders for sewing-machines, and especially the "Singer" 10 or other similar machines wherein the bobbin-winding mechanism is driven from the horizontal rotating machine-shaft; and it has for its object to allow the sewing mechanism to be thrown out of operation when the bobbin-winder is applied to use, and vice versa. 15

This invention is illustrated in the accompanying drawings, in which Figure 1 represents a side view. Fig. 2 is a sectional view, showing the arrangement of the pulley and its driving cog-wheel. Fig. 3 is a vertical cross-section on the line xx , Fig. 1. Figs. 4, 5, and 6 are detail views hereinafter referred to.

Similar letters indicate corresponding parts.

The letter A designates the arm of a sewing-machine, forming the bearing for the horizontal rotating shaft B, which gives motion to the sewing mechanism. To this shaft is fixed the fly-wheel C by means of its hub C', (see Fig. 2,) which latter is elongated, and on which is placed 25 loosely a pulley, D, adapted to connect with the driving-pulley of the machine. The pulley D carries a cog-wheel, D', which, in this example, is integral therewith, and which is a medium for driving the bobbin-winding mechanism, as hereinafter explained. Next to the pulley D, on the elongated hub C' of the fly-wheel, is placed a collar, E, which is fixed to the hub by a pin, v, passing through the shaft B as well as the hub, so that this pin serves 30 also to fix the fly-wheel to the shaft. In the fly-wheel C is arranged a set-screw, F, which is adapted to engage the pulley D by impinging against the side thereof opposite to the collar, and when this screw is tightened to engage 35 the pulley the machine-shaft is caused to share the motion of the latter through the fly-wheel C; but when the screw is retracted to free the pulley the shaft remains stationary, the pulley turning independently thereof to operate 40 the winding mechanism.

The letter G designates a spindle, and H an arm, which receive and hold between them the bobbin to be wound, both being perforated to receive the pivots of the bobbin, and the spindle being, moreover, equipped with a spur engaging the bobbin and causing it to share the motion of the spindle. The spindle G is formed with a transverse or circumferential groove, u, and is so arranged as to be capable of longitudinal as well as a revolving motion in its 55 bearing, consisting of an arm, I, while it carries a pinion, t, at one end. The arm I, forming the spindle-bearing, is secured to the machine-arm A, as by a screw, s, in such a position relatively to the driving cog-wheel D' that by a longitudinal movement of the spindle the pinion can be thrown into or out of gear with the cog-wheel, and hence a revolving motion can be imparted to the spindle, or it can be left stationary, at will. A catch-pin, q, is arranged in the spindle-bearing I to engage the groove u of the spindle by entering such groove, and the relative positions of the groove and pin are such that when the spindle is set to admit the pin to the groove the pinion t is 60 brought in gear with the cog-wheel D' and retained in that position. The spindle, moreover, is subjected to the action of a spring, o, having a tendency to throw it out of gear, so that when the spindle is released this takes 65 place automatically. The spring o also serves to force the spindle up against the bobbin. The inner portion of the spindle G is tapered, as at G', for the purpose of adapting the same to receive a grindstone, a reel, or other similar 70 device; and in order to allow such device to be readily adjusted on the spindle the bobbin-holding arm H is swiveled on a pivot, n, (see Fig. 4,) formed on the end of the spindle-bearing I, so that it can be swung to a lateral position away from the spindle, as indicated by Figs. 4 and 5, a screw, l, Fig. 1, serving to keep the arm in its normal position. 75

The thread to be wound on the bobbin passes through an eye, K, and thence over a segment, J, the latter having its axis in the eye and being opposite to the bobbin, where it is secured to the arm H. A tension device, M, is interposed between the eye K and the spool containing the thread. 80 85 90 95 100

What I claim as new, and desire to secure by Letters Patent, is—

1. The combination, substantially as hereinbefore set forth, with the machine-shaft, of the fixed fly-wheel on such shaft, having an elongated hub, the loose pulley and its driving cog-wheel, arranged on such elongated hub, the collar fixed to the hub next to the loose pulley, the set-screw arranged in the fly-wheel to engage the pulley, and the bobbin-winding mechanism adapted to gear with the driving cog-wheel.

2. The combination, substantially as hereinbefore set forth, with the pulley and its driving cog-wheel, of the transversely-grooved bobbin-holding spindle capable of longitudinal movement, the fixed pinion of the spindle, adapted to gear with the driving cog-wheel, the spring acting on the sliding spindle with a tendency

to throw its pinion out of gear with the driving cog-wheel, and the catch-pin arranged in the spindle-bearing for engaging the groove of the spindle, and thereby retaining the pinion in gear with the driving cog-wheel.

3. The combination, substantially as hereinbefore set forth, of the bobbin-holding spindle, having the inner portion thereof tapered for the reception of a grindstone or other similar device, the fixed spindle-bearing, and the swiveled bobbin-holding arm.

In testimony whereof I have hereunto set my hand and seal in the presence of two subscribing witnesses.

ROBERT STEINER. [L. S.]
